UNITED STATES PATENT OFFICE.

GUSTAVE E. VILLARET, OF NEW YORK, N. Y., ASSIGNOR TO WILLIAM R. NOE & SONS,
OF NEW YORK, N. Y., A CORPORATION OF NEW YORK.

DESIGN FOR A BASE FOR LIGHTING FIXTURES.

Application filed May 25, 1923. Serial No. 6,283. Term of patent 7 years.

To all whom it may concern:

Be it known that I, GUSTAVE E. VILLARET, a citizen of the United States, and residing at New York, in the county of New York and State of New York, have invented a new, original, and ornamental Design for Base for Lighting Fixtures, of which the following is a specification, reference being had to the accompanying drawing, forming part thereof.

Fig. 1 is a side view of a base for lighting fixtures, showing my new design.

Fig. 2 is top view of the base taken on the line 1—1 in Fig. 1 looking in the direction of the arrows, a part of the surface ornamentation only being shown, it being apparent that the remaining surface ornamentation thereon being a repetition of the former.

I claim:

The ornamental design for a base for lighting fixtures, as shown.
